By Walter Vincent Atty.

UNITED STATES PATENT OFFICE.

CHARLES A. HUNT, OF FALL RIVER, MASSACHUSETTS.

DEVICE FOR HITCHING ANIMALS.

SPECIFICATION forming part of Letters Patent No. 398,965, dated March 5, 1889.

Application filed November 30, 1888. Serial No. 292,219. (No model.)

To all whom it may concern:

Be it known that I, CHARLES A. HUNT, of Fall River, in the Commonwealth of Massachusetts, have made certain new and useful

5 Improvements in Devices for Hitching Animals; and I do hereby declare that the following specification, taken in connection with the drawings making a part of the same, is a full, clear, and exact description thereof.

10 Figure 1 is a view of a horse's head with bridle, showing adjustment of my device and hitching-rope secured to post. Fig. 2 is a view of my device, showing the construction and arrangement of the several parts.

15 My invention is more particularly designed for a street or outdoor hitching device, to be used in connection with that portion of the harness termed the "bridle," and it consists in the construction and arrangement of the 20 parts as hereinafter described.

The devices now in common use for street hitching are passed and fastened around the neck of the horse and provided with a snap attached to the hitching-rope near the neck-loop, which is secured to one end of the bit.

25 With hitching devices of this class, in case of a sudden start, the bit is drawn to one side and often with sufficient force to pull the ring or cross-bar into the mouth beyond the ability 30 of the horse to dislodge or clear it, which so pains or frightens him that he will break away. In my invention I overcome these difficulties by so constructing and attaching the device that the pull upon the bit will be exerted evenly upon both sides, and will be directly backward.

In the drawings, A is the hitching device, which is made of rope and has a snap, B, attached to one end.

C is a sleeve attached to the rope at a proper 40 distance from the end, and has a ring or eye, D, into which the snap B works, thus forming the neck-loop.

Below the neck-loop is a ring, E, which slides upon the hitching-rope, being limited in its 45 movement by a chain, F, which connects it with the stationary sleeve C. To the ring E two snaps, G H, are attached by a link or in any other desired way.

In adjusting my device one end is first 50 passed around the neck and the snap B engaged with the ring D, and then the snaps G and H adjusted to the rings I J of the bit, after which the hitching-rope may be secured to the post or other fixed object. The chain 55 F, while giving the ring ample play upon the rope, prevents it from sliding off or from being carried to an inconvenient distance from the neck-loop.

It will be seen that whenever the horse 60 starts forward and exerts a pressure the hitching-rope, operating through the ring E, will exert an even pull upon both sides of the bit, and that such pull will be in the direction of backing the horse.

65 What I claim as my invention, and desire to secure by Letters Patent, is—

A hitching-strap comprising the neck-loop, a loose ring connected by a chain to said loop, and snap-hooks attached to said ring, substantially as described.

C. A. HUNT.
